United States Patent Office.

JOAB H. WOOSTER, OF STRYKERSVILLE, ASSIGNOR TO HIMSELF AND ROBERT DUNBAR, OF BUFFALO, NEW YORK.

Letters Patent No. 67,936, dated August 20, 1867.

IMPROVEMENT IN STEAM-ENGINE GOVERNORS.

The Schedule referred to in these Letters Patent and making part of the same.

TO ALL WHOM IT MAY CONCERN:

Be it known that I, JOAB H. WOOSTER, of Strykersville, Wyoming county, and State of New York, (assignor to myself and Robert Dunbar, of Buffalo, New York,) have invented a certain new and improved Governor for Steam Engines; and I do hereby declare that the following is a full and exact description thereof, reference being had to the accompanying drawings, in which—

Figure I is a side elevation.

Figure II is a top plain view.

Figure III is a detail sectional view.

The nature of this invention consists, first, in the arrangement of the governor-balls upon arms or rods radiating from the driving-shaft of a steam engine, and the connection of the arms of such balls with the eccentric, which operates the cut-off valve in manner herein set forth, so that the outward movement of the balls will be communicated to the eccentric and thereby control the cut-off; second, in the eccentric being loosely arranged on the driving-shaft, in connection with the governor, the governor holding the eccentric and changing and controlling its lead.

Letters of like name and kind refer to like parts in each of the figures.

The governor-balls A A are placed upon the radial arms B B in a manner to allow them to move outwardly and inwardly upon said arms. The said arms are attached to and radiate from the driving-shaft at any convenient location. They may be attached by means of a hub, or otherwise, or they may be attached between the spokes of the fly-wheel, as shown in the drawings, the place of attachment being a matter of choice or convenience. A spiral spring, C, is connected with each governor-ball and coiled around the radial arm, and also attached at its opposite end to the lug c¹, secured between two adjusting screw-nuts c² near the hub. D represents the eccentric, which is placed loosely upon the shaft, and is connected with the cut-off valve E by means of the connecting-rod E'. The eccentric has a hub, d', projecting from the side next to the governor-balls. F is the eccentric of the slide-valve F², which eccentric is made fast on the shaft, and F¹ is its connecting-rod. G represents a collar, having crank-like extensions h, which is connected to the hub d' of the loose eccentric by means of the set-screws g'. The crank extensions of the collar are each connected to the governor-ball by means of the rods h'.

The adjustable springs are made to oppose a given force to the outward movement of the governor-balls.

The eccentric, which is in connection with the cut-off valve, being placed and used loosely upon the shaft, and being connected with the governor, and being held and controlled by the governor, as before described, it is evident that the governor will act directly upon the eccentric to change and determine its lead, and thereby control the cut-off.

All the parts may be set so as to give any required velocity to the driving-shaft, and so as to cut off steam at any required part of the stroke.

What I claim as my invention, and desire to secure by Letters Patent, is—

1. The arrangement of the governor-balls A, sliding on rods B B, radiating from the driving-shaft of a steam engine, and held by coiled springs C, their arms h' connecting with the eccentric, which operates the cut-off valve in such manner that the outward movement of the balls will be communicated to the eccentric and thereby control the cut-off, substantially as described.
2. The connection of the rod h' to the eccentrics, consisting of the hub d', collar G, with crank-like extensions h, connected to the hub d' by the set-screw g', constructed and arranged as set forth.

J. H. WOOSTER.
